schaft mit beschränkter Haftung, Frankfurt
am Main, Germany, a joint-stock company of
Germany

Application October 17, 1952, Serial No. 315,301

9 Claims. (Cl. 101—235)

1

The present invention relates to franking machines which are used for printing a stamp replacing an adhesive stamp on letters, postcards, or other matter to be forwarded by mail.

In one type of prior art franking machines a stamp is printed directly on the matter to be forwarded by mail. In another prior art franking machines stamps are being printed on a strip of paper or tape drawn from a storage roller whereupon, the strip or tape is subdivided by a cutting device of the machine into individual lengths usable for franking newspapers, periodicals and the like. It has also been suggested to adapt franking machines for printing stamps directly on letters and the like mail for successive printing of stamps on tape. In one type of these last referred-to machines the end of a tape is being moved forward by a printing roller out of the initial printing position and fed to a cutting device which cuts off the printed end from the tape, whereupon the unused end thereof is returned to the printing position. In an alternative arrangement, a length of tape to be printed is being cut off and the cut-off length then fed to the printing roller. This type of franking machine has an automatic control of the printing roller responsive to the feed of the matter to be printed and can also be employed for printing on paper tape. In both arrangements, a guide for the paper tape, a feeding device therefor and a cutting device are combined to form a structural unit which can be added at will to the frame of the franking machine. With both arrangements it is however only possible to obtain the intended mode of operation by interfering with the driving mechanism of the franking machine and by adding auxiliary steps of operation.

It is an object of the invention to provide a simple franking machine which is capable of being used selectively for printing stamps either on individual matter to be forwarded by mail, such as letters, or postcards, or on paper strips or tape.

Another object of the invention is to provide a franking machine for such selective use without the necessity of interfering with the driving mechanism of the machine on change from one mode of use to the other.

A further object of the invention is to provide a franking machine for printing stamps on strips of paper and cutting the strips, wherein the strips are always fed through the machine in the same direction.

Still another object of the invention is to modify a franking machine with an automatic control of its printing roller responsive to the feed

2

of the matter to be printed in a simple manner in such a way that it is possible to feed a strip of paper drawn from a storage device into and through the machine without subdividing the strip, without changing the direction of the movement thereof, and with a constant but pre-settable speed, and thus to print successively spaced stamps on such strips.

These and other objects and advantages of the invention will become apparent to those skilled in the art from the following detailed description of an embodiment of the invention, when read in conjunction with the appended drawings, which are given by way of example only and in which:

15 Fig. 1 is a perspective view of a franking machine embodying the invention;

Fig. 2 is a front elevational view of the same machine as shown in Fig. 1; and

20 Fig. 3 is an electric circuit diagram of the machine of Figs. 1 and 2.

According to the invention, an electric main contactor operable by an electric motor for driving a printing roller at regular time intervals corresponding to the sequence of prints on a paper strip is provided in an electric control circuit for the printing roller in series with an auxiliary contactor which is kept closed by a paper strip while the strip is being fed through the machine, whereby to enable stamps to be successively printed on the strip, each print being effected by the closing of the main contactor. The auxiliary contactor operable by the paper strip only prepares the control circuit for the printing roller, while the main contactor operable by the electric motor closes the said control circuit at regular time intervals. The auxiliary contactor is kept closed only during the feed of the strip and thus breaks the control circuit when the feed of the strip is terminated. The auxiliary contactor also breaks the control circuit and thereby prevents a further operation of the printing roller when the paper strip becomes accidentally torn. The electrically controlled mechanism of the franking machine is inexpensive and may easily be added to an existing franking machine.

50 Preferably, a further contactor is provided in the electric control circuit and is controllable by a counting device for counting the number of stamps printed on the strip in such a manner that said further contactor is opened when a number of prints which is predetermined by the setting of the counting device have been effected.

In order to enable stamps to be printed on pieces of tape of different lengths, a plurality of main contactors may be provided which are oper-

able by the electric motor at regular time intervals different for each contactor, one of the said main contactors being insertable at will into the electric control circuit for the printing roller. Preferably an electric change-over switch is provided in the control circuit for the printing roller which bridges the main contactor or contactors operable by the electric motor at regular time intervals and also the further contactor, if any, in its position for directly franking letters. In its other position or positions intended for printing stamps on paper tape which positions correspond to the number of main contactors this change-over switch inserts the main contactor or one of the main contactors, and also the further contactor, if any, into the electric control circuit.

The drawings show, a manually operable stamping device 2 removably attached to a base 1 of a franking machine. When the stamping device 2 has been detached, it may be removed from the frame 1 and may be used manually for printing stamps on any suitable object. For mechanically operating the stamping device 2 when attached to the base 1 of the franking machine, an electric motor 3 is provided which is likewise mounted on the base 1.

In front of the inlet of the franking machine a removable table 5 is provided for supporting letters or postcards to be franked. When it is intended to successively print stamps on a strip of paper or tape, the table 5 is replaced by a bracket 6 for a paper roll 7. At the outlet of the franking machine, a removable cutting device 8 is provided for cutting the stamped strip of paper at regular intervals. Between the inlet of the franking machine and the stamping device 2, a switching mechanism 9 is provided which is adapted to be operated by the matter to be franked. The electric motor 3 drives one of a pair of conveyer rollers 11 by means of a suitable gear, a conveyer belt 4 being placed around and being driven by said rollers. Counter-pressure rollers 13 press against conveyer belt 4. The electric motor 3 also drives a first member 15 of a dog-clutch by means of a chain 14, and a cam-shaft 17 by means of a reduction gear 16. Printing roller 18 of the stamping device 2 is mounted adjacent to conveyer belt 4. The printing roller 18 is operatively connected to a shaft 21 carrying a second member 20 of the dog-clutch by means of an intermediate gear 19. The second member 20 of the dog-clutch is urged by a spring (not shown) in the direction towards the first member 15 of the dog-clutch, but is normally prevented from moving in this direction by a locking lever 24 controlled by an armature 22 of an electromagnet 23. The locking lever 24 bears against a projection 25 of a disc keyed to the shaft 21. Matter to be stamped and placed onto the conveyer belt 4 passes a tiltable lever 26 arranged in front of the stamping device 2. A permanent magnet 28 is arranged adjacent a mercury switch 27, and is mechanically tied to the tiltable lever 26. Within the mercury switch 27, a solid contact member 31 is fixed to a resiliently supported iron arm 29 arranged opposite a cup 30 containing mercury, the solid contact member 31 being normally lifted out of the mercury in the cup 30 under the action of the permanent magnet 28 on the iron arm 29. When matter to be stamped and placed onto the conveyer belt 4 reaches the tiltable lever 26, the same rotates the permanent magnet 28 to such an extent away from the mercury switch 27 that the solid contact member 31 drops into the mercury in the cup

30 owing to the weight of the iron arm 29, whereby the mercury switch 27 is closed. The cam-shaft 17 carries three cams 32, 33 and 34, of which the cam 32 has one projection, the cam 33 has two projections arranged diametrically opposite to each other, and the cam 34 has three projections equally distributed along the periphery of the cam. Each of the cams 32, 33 and 34 cooperates with one of three contactors 35, 36 and 37 formed by sets of contact springs controllable by the corresponding projection or projections of the cams. When shaft 17 is rotated the projections on cams 32, 33 and 34 engage the contact springs of contacts 35, 36 and 37 and effect contact between them.

The shaft 21 carries a cam 38 acting on a rotatable lever 39 of a subtracting counting device 40. A desired number of stamps to be printed may be predetermined by means of rotatable knobs 41 provided on said counting device. The predetermined number of stamps appears behind the windows 42 of counting device 40. On each complete revolution of the cam 38, the predetermined number is reduced by one digit. The counting device 40 comprises a further contactor 43 which is kept closed as long as the number shown by the counting device 40 is different from zero, and the further contactor 43 is opened when the counting device is down to and indicates zero.

A two-wire line 46 for energizing the electric motor 3 terminates in a plug 45 and includes a double-pole switch 47 and the exciting or energizing coil 48 of the electromagnet 23 and the switching mechanism 9 forming an auxiliary contactor arranged in series with the exciting coil 48. The above circuit includes four terminals 51, 52, 53 and 54 of a two-stage change-over switch 50. Mechanism 9 is either directly connected to the terminal 51 of switch 50 or across one of the main contactors 35, 36, 37, controlled by the cams 32, 33, and 34 to one of the terminals 52, 53, and 54 of switch 50. Furthermore, the circuit includes terminals 55, 56, 57 and 58 of the second stage of change-over switch 50. The portion of switch 50 shown at the right of Fig. 3 may, either be directly connected to the terminal 55, or across the further contactor 43 to the terminals 56, 57 and 58. The second stage of the change-over switch 50 shown at the left of Fig. 3 is connected over a fuse 59 to the double-pole switch 47. The driving electric motor 3 is shunted across the two wires of the energizing line or, to be more specific, is branched off between one pole of the double-pole switch 47 and the exciting or energizing coil 48 of the electromagnet 23. Motor 3 is connected to the switching lever of the change-over switch 50 which co-operates with the terminals 51 to 54. When the two switching levers of the change-over switch 50 are placed on terminals 51 and 55, respectively, as shown in Fig. 3, the contactors 35, 36 and 37 controlled respectively by the cams 32, 33 and 34, as well as the further contactor 43 are bridged or shunted out. Change-over switch 50 is placed in this position which will briefly be referred to by the abbreviated term "letter" when it is intended to print directly on letters or postcards. However, when the switching levers of the change-over switch 50 are positioned on one of the pairs of terminals 52, 56; or 53, 57; or 54, 58, then, in each case, one of the contactors 35, 36, and 37 controlled, respectively, by the cams 32, 33 and 34, and also the further contactor 43, controlled by the counting device 40, are effective.

5

Since the cams 32, 33 and 34 are driven by the electric motor 3 with a constant speed, the contactors 35, 36, and 37 are periodically closed and opened but each at different time intervals. Now, depending on the position of the change-over switch 50, that is to say depending on which one of the contactors 35, 36 and 37 has been rendered effective in each case, the electric control circuit is periodically closed and opened but the time intervals are different for each of the three contactors. The terminals 52, 53 and 54; and 56, 57 and 58 are rendered effective when it is intended to print stamps onto a paper strip or tape. The corresponding positions in which the change-over switch 50 is placed when it is intended to print on a paper will be referred to by the abbreviation "strip."

When the double-pole switch 47 is closed after insertion of the plug 45 into a corresponding socket of the main supply, the electric motor 3 is started and drives the conveyer belt 4 as well as the chain 14. When the change-over switch 50 is in position "letter," the electric circuit for the electromagnet 23 operating the dog-clutch is closed each time a letter passes the tiltable lever 26 of the switching mechanism 9, causing the locking lever 24 to release the printing roller 18 while it is coupled to the electric motor 3 by the dog-clutch to perform one revolution and to print a stamp on to the letter carried through the machine by the conveyer belt 4. The time interval between the operation of the tiltable lever 26 by a letter and the release of the iron arm 29 is so selected that the letter to be franked reaches the printing roller 18 during this interval. Each franking print is counted by the counting device 40 of the stamping device 2. When the change-over switch 50 is brought into one of the positions "strip," then the auxiliary contactor formed by the switching mechanism 9 remains closed during the passage of a strip through the franking machine inserted into it. The electric circuit prepared by switching mechanism 9 is closed by one of the main contactors 35, 36 and 37 operated by the electric motor 3 at regular intervals of time whereby on each closing of the respective contactor the electromagnetically operated dog-clutch causes one single revolution of the printing drum which performs one print on the strip. The number of prints on the strip is being counted by the counting device 40. The cutting device 8 arranged at the outlet of the franking machine and operated by the armature 22 of the electromagnet 23 cuts off a desired length of the strip after each print. When a predetermined number of prints have been made on a tape, the electric control circuit is interrupted by the further contactor 43 of the counting device 40. The cutting device 8 comprises a sleeve 60 fixed on a frame or casing of the franking machine. Sleeve 60 has slots 61 and 62 of different width at the front and the rear, respectively. A roller 63 is rotatably mounted within the sleeve 60 and has a conical slot 64 extending through it. The limiting edges of the slot 64 at the narrowest region thereof operate as cutting edges. In its initial position, the conical slot 64 registers with the slot 62 at the rear of the sleeve 60. The roller 63 is tied mechanically to the armature 22 of the electromagnet 23 in such a manner that each time the armature 22 is attracted, the roller 63 performs a limited rotation. A paper strip 65 threaded through the slots of the sleeve 60 and of the roller 63 is cut off by the rotational movement of the roller 63 caused on each excitation or en-

6

ergization of the electromagnet 23. After the cutting process has been terminated, the conical slot 64 of the roller 63 guides the paper accumulated therein during a cutting process towards the slot 62 of the sleeve 60. The cutting device 8 as well as the table 5 and the bracket 6 for holding the paper roll 7 may be connected to the frame or casing of the franking machine by a clamp lock which is easily releasable.

10 The spacing of successive prints on the strip or tape depends on the number of projections on the cams 32, 33, 34 for operating the main contactors 35, 36, 37, respectively, which are rendered effective in the "strip" positions of the change-over switch 50. When the number of projections is increased, the electromagnet 23 operates the dog-clutch at correspondingly shorter time intervals, whereby the strip or tape running through the machine is provided with stamp prints at shorter distances. According to the desired length of the cut-off pieces of the strip, the cams 32, 33 and 34 may be exchangeable against others having greater numbers of projections. If the paper strip should tear during the operation of the device, the 20 switching mechanism 9 operating the mercury switch 21 relapses, whereby the solid contact member 31, owing to the iron arm 29 being now attracted by the permanent magnet 28, is lifted from the mercury cup 30 opening the mercury switch. Thereby the electromagnet 23 for operating the dog-clutch is disconnected so that the printing roller 18 is rendered inoperative. The 25 printed lengths cut off from the paper strip or tape may subsequently be fed through an addressing machine providing the lengths of the paper strip with addresses.

I claim:

1. A franking machine comprising means for feeding matter to be franked through said machine, a printing roller for printing a franking stamp on such matter, a drive, a clutch for coupling said drive to said printing roller, an electric control circuit, means in said circuit for operating said clutch to cause said printing roller to 40 perform a revolution when said control circuit is closed, an electric main contactor in said circuit, said main contactor being operable by said drive to make and break said control circuit at regular intervals of time to cause the printing 45 roller to print franking stamps at regular distances on tape fed through said machine, and an electric auxiliary contactor arranged in said control circuit in series with said main contactor, and operable by the matter to be printed while fed through said machine to prevent continued printing when the feed of the tape is interrupted, contactor making and breaking the control circuit at regular time intervals to cause the printing roller to print franking stamps at regular 50 distances on to the strip, the auxiliary contact preventing the printing when the feed of the strip is interrupted.

2. A franking machine as claimed in claim 1, wherein a plurality of main contactors are provided in the electric control circuit, the said main contactors being all operable by the drive to make and break said control circuit at regular time intervals of different lengths for different main contactors, means being provided for alternatively rendering one of the main contactors effective, whereby to alter the distances between stamps printed on a strip in dependence on the main contactor rendered effective.

3. A franking machine as claimed in claim 2, wherein a plurality of cams are inserted between

the drive and the main contactors for operating the same, the plurality of cams corresponding to the plurality of main contactors, each cam operating one of the main contactors, at least one projection being provided on each cam so that the numbers and arrangements of the projections on the cams determines the regular time intervals at which the contactors are operated by the drive over the cams to make and break the control circuit.

4. A franking machine as claimed in claim 3, and comprising a reduction gear between the drive and the cams.

5. A franking machine as claimed in claim 2, and comprising a change over switch in the electric control circuit which in one position bridges the main contactors and the further contactor to render the same ineffective for printing stamps on the separate matters, and in each of its other positions, the number of which corresponds to the plurality of main contactors, renders one of the main contactors and the further contactor effective for printing stamps on to a strip of material.

6. A franking machine as claimed in claim 2, and comprising a frame housing the drive, the printing roller forming part of a manually operable stamping device releasably coupled to said drive, the electric control circuit for said drive comprising the auxiliary contactor, the plurality of main contactors and the further contactor.

7. A postage printing machine comprising a tape feeding device, a printing roller supplied with tape from said feeding device, motor means for operating said printing roller, a clutch for selectively coupling and uncoupling said motor means and said printing roller, an electric control circuit, a magnetic means energizable by the flow of current in said circuit to operate said clutch to couple said motor means and said printing roller, a first switching device arranged in said circuit operable by said motor means to effect periodic opening and closing operations of said circuit to cause periodic operation of said printing roller to make a plurality of equidistant imprints on said tape, a second switching device arranged in said circuit in series with said first switching device, and means under the control of said tape when fed from said feeding device to said printing roller for controlling said second switching device to interrupt said circuit to stop the operation of said printing roller upon interruption of the feed of said tape.

8. A postage printing machine comprising a tape feeding device, a printing roller supplied

with tape from said feeding device, motor means for operating said printing roller, an automatic clutch for selectively coupling and uncoupling said motor means and said printing roller, an electric control circuit, an electromagnet energizable by the flow of current in said circuit, a linkage operated by said electromagnet to operate said automatic clutch to couple said motor means and said printing roller, a first switching device arranged in said circuit and operable by said motor means, said first switching device comprising a plurality of pairs of contacts each operable to effect a different number of periodic opening and closing operations of said circuit in a given interval of time to cause periodic operation of said printing roller to make a plurality of equidistant imprints on said tape, a plurality of different cam means operated by said motor means each effecting relative movement of one of said plurality of pairs of contacts to cause said periodic opening and closing operations of said circuit, a second switching device arranged in said circuit in series with said first switching device, and means under the control of said tape when fed from said feeding device to said printing roller for controlling said second switching device to interrupt said circuit to stop the operation of said printing roller upon interruption of the feed of said tape.

9. A franking machine as claimed in claim 1 comprising a subtracting counting device adapted to be manually pre-set on a pre-determined number, means controlled in accordance with the rotary motion of said printing roller to subtract the number of stamps printed by said printing roller from the predetermined number manually pre-set in said counting device, a further contactor arranged in the electric control circuit for maintaining said circuit closed as long as the difference determined by said counting device differs from zero, and means controlled by said counting device for opening said further contactor on completion of the pre-set number of prints to break said control circuit to preclude continued printing by said printing roller upon completion of the pre-set number of prints.
